UNITED STATES PATENT OFFICE.

FRANZ XAVER BODNAR AND SAMUEL LEIB KREPPPEL, OF VIENNA,
AUSTRIA-HUNGARY.

COIN-OPERATED LOCK MECHANISM.

SPECIFICATION forming part of Letters Patent No. 610,578, dated September 13, 1898.

Application filed February 20, 1897. Serial No. 624,464. (No model.) Patented in England August 22, 1896, No. 17,453; in Switzerland September 28, 1896, No. 13,253; in France November 18, 1896, No. 258,540; in Germany April 21, 1897, No. 92,906, and in Austria May 20, 1897, No. 47/1,809.

To all whom it may concern:

Be it known that we, FRANZ XAVER BODNAR and SAMUEL LEIB KREPPPEL, citizens of Austria-Hungary, and residents of Vienna, 5 Austria-Hungary, have invented certain new and useful Coin-Operated Lock Mechanism, of which the following is a specification.

Patents have been granted for this invention in Austria, No. 47/1,809, dated May 20, 10 1897; in Germany, No. 92,906, dated April 21, 1897; in France, No. 258,540, dated November 18, 1896; in England, No. 17,453, dated August 22, 1896, and in Switzerland, definitive, No. 13,253, dated September 28, 15 1896.

Our invention is a coin-controlled portfolio adapted for the reception of papers and documents, and it is capable of variation as to form to suit different requirements as to shape 20 and size necessitated by the different kinds of papers or documents to be contained.

Our invention is particularly adapted for use in connection with newspapers or periodicals which may be inclosed therein from inspection and use until the required coin is introduced into the device to release the locking mechanism.

In the drawings, Figure 1 is a perspective view of the portfolio or binder. Fig. 2 is a view 30 of the portfolio open. Fig. 3 is a view of the lock with part of the casing removed. Fig. 4 is a sectional view on line 3 3 of Fig. 3. Figs. 5 and 6 show details of the locking-bolt and catch-hook. Fig. 7 is a detail view 35 of a paper-clamp.

The portfolio or temporary binder consists of two leaves or sides 1 2, hinged together at top and bottom. The hinges comprise the sections 3, secured to the sides, and the connecting-pieces 4, hinged to the said sections by hinge-joints, thus forming a double hinge connection which will keep the sides at the back a fixed distance apart and will insure the alinement of the locking devices herein- 40 after described. The connecting-pieces 4 support the clips which hold the rod by which the papers or documents are held.

The locking mechanism is placed between the leaves or sides at or near their free edges,

and this mechanism comprises a catch 6 on one leaf projecting at right angles to the face of the leaf and adapted to pass through an opening 7 in the side 8 of the lock-casing 9, which casing is fixed by screws or otherwise in an opening in the opposite leaf. A locking-bolt 55 10 engages with its end the notch 11 of this catch, and thus locks the leaves together. The bolt is carried by an arm 12, pivoted to a plate 13, which is screwed to the frame-bars 14 of the face-plate 15 of the lock-casing, so 60 that the arm moves between this face-plate 15 and the plate 13. A spring 16, also between the plates, presses the arm constantly in a direction to normally engage the locking-catch. The bolt is bent up from the lever-arm, so as to overlie the reduced part 13' of the plate 13 and to pass through the upright guide 13" thereon. The lever-arm has a stud or projection 17 on one side adjacent to the edge of the cam-slide 18, which is located 65 between the plates 15 and 13 and is guided by a pin 19 thereon, working in a slot 20 of the plate 13, and by the handle or knob 21, passing from the slide through a slot in the face-plate of the lock-casing. The coin-slide 70 has an opening 22 to receive the coin of proper size from the coin-slot 23 in the face-plate 15, and the slide is pressed normally up by a spring 24, carried on the inner side of the plate 13 and engaging the slide, so that 75 its opening is normally in position to receive the coin from the coin-slot. A spring 30 is secured to the face of the plate 13, and the end of this is bent to lie in the line of movement of the coin. The opening in the coin-slide 80 extends to the edge of the slide, and the coin when in the opening projects slightly therefrom, and when the slide is moved the edge of the coin bears directly on the projection 17 of the bolt-lever 12. This action forces 85 the lever-arm backward and retracts the bolt sufficiently to unlock the portfolio. The lever-arm 12 has a pin 12' thereon, and this is engaged by a retaining-lever 25, which has a forked end 25' to engage the pin when the lever-arm 12 is retracted. The retaining-lever 90 is set in position to engage the pin 12' immediately after the lever-arm is retracted, and for 95

this purpose the retaining-lever is of right-
angular form and is pivoted at its elbow to the
face of the plate 13, its arm 25" having a cam
edge which extends across the slot 20 before
mentioned and into the path of the pin 19 on
the coin-slide, being normally pressed into
this position by the leaf-spring 26, bearing on
the arm 25", and having its other end secured
to the plate 13 by the pin 27.

10 In the movement of the coin-slide with the
coin in place the lever-arm of the bolt is first
retracted through the direct action of the
coin, and then the pin 19 strikes the cam edge
of the right-angular retaining-lever and
moves said retaining-lever against the pres-
sure of its spring, so that its hook 25' will be
directly in front of the pin 12' just at this
time, and while the retaining-lever is so held
the coin in the continuous movement of the
15 slide releases the projection of the lever-arm
and allows the lever-arm to have a very slight
movement under the action of its spring, so
that the pin 12' will firmly engage the hook
of the pivoted retaining-lever. The operating-
knob of the coin-slide now being released
20 by the operator, said slide will return at once
to its former position, while the locking-bolt
will remain retracted by the pivoted catch-
lever. The bolt is not retracted far enough
25 by the coin to get entirely out of alinement
with the catch-hook 6 on the other leaf or
side of the portfolio; but it is simply retracted
far enough to destroy the locking action of
the bolt. The bolt and catch may still have con-
30 tact with each other; but this contact is a
sliding one and is intended merely to give in
the final separation of the catch-hook from
the locking-bolt a slight refracting move-
ment to the latter sufficient to release the pin
35 12' from the pivoted retaining-lever and allow
the locking-bolt to be set free to engage the
catch-hook when the portfolio is closed.

It will be seen from Figs. 5 and 6 that the
catch-hook has a flat surface 28 for engaging
40 the locking-bolt to secure the full locking
effect and a rounded or inclined bearing-surf-
face 29 to engage the inclined end of the lock-
ing-bolt.

When the parts are locked, the bolt en-
gages the flat part of the catch-hook, and
50 when the bolt is retracted by the coin its in-
clined end is brought into alinement with the
incline on the catch-hook, and in the final
opening movement of the catch-hook or sepa-
55 ration of the same from the locking-bolt this
incline, acting against the inclined edge of the
locking-bolt, will retract the latter sufficiently
to release the bolt from the retaining-lever
25, and immediately the catch-hook leaves
60 the bolt the latter resets itself for another
locking action, as do also all the other parts.

The coin when introduced through the coin-
slot must be forced by the operator under
the bent end of the spring 30, and this spring
65 by bearing upon the face of the coin steadies
it in its movement. This spring will also

prevent the withdrawal of the coin when once
it has been used to operate the device.

The casing 13 has an opening 13^x through
which the coin may fall into the bottom of
70 the casing, from where it may be removed
through the door 31 when the same is unlocked
by operating the lock 32, carried on the door.

The casing-plates and operating parts may
be stamped up into shape.

In order to hang up the portfolio, each leaf
or side has attached to its upper edge a hook
75 33, facing in opposite directions, so that when
the leaves are closed these hooks, overlapping
each other, will form a suspending-ring.

80 It will be noticed that in our invention the
weight of the coin plays no part at all, but
that the parts are operated entirely by direct
contact of the coin transmitting the force
applied by the operator to the cam-slide.

85 Our invention is not limited in its applica-
tion to portfolios, but may be used on draw-
ers and in like situations, and the mechanism
may be used in any position—vertical, hori-
zontal, or, in fact, upside down.

90 If the cam-slide is operated without the
presence of a coin therein, the locking-bolt
will not be retracted. The retainer will be
operated; but this will have no effect, as the
pin 12' will simply be received in the notch
95 V of the retaining-lever, and the retaining-
lever will again assume normal position as
soon as the coin-slide is released. This ac-
tion of the retaining-lever with its notch V
will for the time being effectually lock the
100 bolt against retraction, and thus the device
cannot be successfully tampered with.

The newspapers may be held in place on the
rod before mentioned by a tubular clamp X.

A plate y is used to cover the retaining-lever,
105 its spring, and the bolt.

What we claim is—

1. A coin-operated lock mechanism com-
prising a swinging bolt, a lock-hook adapted to
be engaged thereby, a movable coin-carrier
110 having a recess to receive the coin, a projection
on the bolt adapted to be engaged by the coin
and be moved thereby to unlock the bolt,
and means for holding the swinging bolt in
its retracted position, substantially as de-
115 scribed.

2. A coin-operated lock mechanism com-
prising a spring-pressed bolt, a lock-hook
adapted to be engaged thereby, a movable
120 coin-carrier having a recess to receive the
coin, said spring-pressed bolt having a por-
tion extending into the path of the coin
whereby the movement of the coin and coin-
slide will move the bolt, and a retaining-lever
adapted to be operated by the coin-carrier to
125 engage the bolt and hold it retracted, the said
locking-hook in its final opening movement
acting to release the retaining device from
the locking-bolt substantially as described.

3. A coin-operated lock mechanism com-
prising the spring-pressed swinging bolt, the
lock-hook adapted to be engaged thereby, the

reciprocating coin-carrier having a recess to receive the coin, said swinging bolt having a portion extending into the path of the coin, and the spring-pressed oscillating retaining-lever having one end adapted to be operated by the coin-carrier and the other end adapted when so operated to engage the swinging bolt, substantially as described.

4. In combination the spring-pressed locking-bolt, the lock-hook, the movable coin-carrier adapted to receive a coin and carry it into contact with said locking-bolt to move the same, a projection carried by the locking-bolt, and a retaining-lever operated by the movement of the coin-carrier to hold the locking-bolt in its moved position, said retaining-lever having a notch adapted to engage the projection and hold the bolt against movement when no coin or an improper coin has been placed in the carrier, substantially as described.

5. In combination the swinging bolt under spring tension, the lock-hook, the reciprocating coin-carrier having a recess for the coin, the projection from the bolt extending into the path of the coin, the spring-pressed two-armed retaining-lever having one arm adapted to be moved by the coin-slide, the other arm of said lever having its end adapted to abut against a projection on the swinging bolt to hold it unlocked when the proper coin has been placed in the carrier, and having a

V-shaped notch adapted to embrace said projection to hold the swinging bolt against movement when the carrier is improperly operated, substantially as described.

6. In combination with a movable receptacle, a lock mechanism comprising the reciprocating coin-carrier having slots, a spring-arm 30, a swinging arm carrying the bolt, the projection on the said swinging arm, the retaining-lever and the pin on the swinging arm to be engaged thereby, said retaining-lever having a notch to receive the pin in one position of the parts, substantially as described. 45

7. In combination with a portfolio, a casing carried by one cover, a locking-hook carried by the other and adapted to penetrate the casing, a spring-pressed locking-bolt adapted to engage the hook, a reciprocating coin-carrier having a recess for a coin, said locking-hook having a portion extending into the path of the coin, and a spring adapted to bear against the coin to hold it in the recess and acting also to drop behind the coin on 55 the movement of the carrier to prevent its extraction, substantially as described.

Signed at Vienna, Austria-Hungary, this 25th day of January, A. D. 1897.
